United States Patent

Des. 240,248
Patented June 8, 1976

240,248

GAME TARGET

Gerard Andrew Himmelman, 379 Gordons Corner Road,
Englishtown, N.J. 07726

Filed Nov. 11, 1974, Ser. No. 522,901

Term of patent 14 years

Int. Cl. D21—01

U.S. Cl. D34—5 PP

Fig. 1.

Fig. 2.

FIG. 1 is a front elevational view of a game target, showing my new design.

FIG. 2 is a side elevational view thereof.

The rear of the game target showing my new design is plain and unornamented.

I claim:

The ornamental design for a game target, substantially as shown and described.

References Cited

UNITED STATES PATENTS

1,212,942	1/1917	Hart	273—102 A
D. 173,969	2/1955	Raines	D34—2 C

MELVIN B. FEIFER, Primary Examiner